UNITED STATES PATENT OFFICE.

CHARLES W. LUTTRELL, OF BRONTE, TEXAS.

FAN ATTACHMENT FOR SEWING-MACHINES.

1,125,141.

Specification of Letters Patent. Patented Jan. 19, 1915.

Application filed April 15, 1914. Serial No. 831,999.

To all whom it may concern:

Be it known that I, CHARLES W. LUTTRELL, a citizen of the United States, residing at Bronte, in the county of Coke and State of Texas, have invented a new and useful Fan Attachment for Sewing-Machines; and I do hereby declare the following to be a full, clear, and exact description of the invention, such as will enable others skilled in the art to which it appertains to make and use the same.

This invention relates to a new and useful improved fan attachment for sewing machines, and an object of the invention is to construct a fanning attachment having connections with the pedal of the sewing machine, so as to automatically actuate the fan, as the pedal is operated.

One of the features of the invention is the provision of adjustable connections between the fan and the pedal, so as to increase or decrease the movement of the fan.

In practical fields the details of construction may necessitate alterations, falling within the scope of what is claimed.

The invention comprises further features and combination of parts, as hereinafter set forth, shown in the drawings and claimed.

In the drawings:—Figure 1 is a view showing the improved fanning attachment as applied to a sewing machine. Fig. 2 is an enlarged detail view of the fanning attachment detached, showing the details of construction.

Referring to the drawings, 1 designates the usual form of sewing machine, while 2 denotes the bracket standard secured by a clamping connection 3 to the machine top. This clamping connection comprises the clamp 3^b having the spaced apart lugs between which the machine top bed plate engages, there being the thumb screw 3^a passing through one of the ears for clamping the clamp in place. This standard is held adjustable in the clamp by means of the set screw 4. On the lower end of the standard below the clamp is a guide member 5 secured in place by thumb screw 6. The guide part has a pivotal movement and is designated by the numeral 7, and through it the pitman 8 is slidably guided. The lower

end of the pitman is connected at 9 to the pedal 10 of the sewing machine. The connection 9 comprises the bolt 9^a, which passes through the slot 9^c of the arm of the pedal, 55 and is provided with a thumb nut 9^b. By this construction the lower end of the pitman is held adjustable with the pedal. The upper end of the pitman has an adjustable connection 11 with one arm of the bell crank 60 fan lever 12. In the arm 13 of which the fan 14 is adjustably and removably attached, as shown at 15. The fan lever is adjustably connected as at 16 to a holder 17, which is slidably and adjustably mounted 65 on the bracket standard 2, by means of the set screw 19. It will be observed that the various parts may be adjusted, so as to increase or decrease the movement of the fan. Also a stiff fan may be substituted for a 70 flexible fan, and vice versa, or the fan may be lowered or raised, so as to be arranged in different positions relative to the machine operator. As the pedal is operated the fan is oscillated, thereby keeping the operator 75 cool.

The invention having been set forth, what is claimed as new and useful is:—

In combination, a bracket standard, a clamp holder through which the standard 80 passes and is adjustably arranged, said clamp holder being clamped to a sewing machine, a pitman having its lower end pivotally connected to the pedal of the machine, an oscillating guide adjustably mounted 85 upon the bracket standard, and through which said pitman is guided, a holding bracket adjustably mounted upon the upper end of the standard, a bell crank fan lever pivotally and adjustably mounted in 90 the holding bracket and having one arm adjustably connected to the upper end of the pitman, and a fan adjustably mounted in the other arm of said lever.

In testimony whereof I have signed my 95 name to this specification in the presence of two subscribing witnesses.

CHARLES W. LUTTRELL.
